UNITED STATES PATENT OFFICE

118,012

DESIGN FOR A PIVOT HINGE

Forrest C. Garrison, Highland Park, Ill., assignor
to The Oscar C. Rixson Co., Chicago, Ill., a
corporation of Illinois

Application October 13, 1939, Serial No. 87,647

Term of patent 14 years

To all whom it may concern:

Be it known that I, Forrest C. Garrison, a citizen
of the United States, residing at Highland Park,
in the county of Lake and State of Illinois, have
invented a new, original, and ornamental Design
for a Pivot Hinge, of which the following is a
specification, reference being had to the accom-
panying drawing, forming part thereof.

Figure 1 is a plan view of the pivot hinge.

Figure 2 is a front elevation.

Figure 3 is a rear elevation.

I claim:

The ornamental design for a pivot hinge, as
shown.

FORREST C. GARRISON.
